ARC LAMP AND CONTROL CIRCUIT
THEREFORFielding C. Coates, Los Angeles, Calif., assignor to
Mole-Richardson Co., Los Angeles, Calif., a
limited partnership of California

Application April 12, 1938, Serial No. 201,550

11 Claims. (Cl. 176—12)

My invention relates to electric arc lamps and has particular reference to a control device and system for accurately controlling the feeding of carbon electrodes employed in such lamps.

5 In carbon electrode arc lamps it is desirable to maintain the arc length as nearly at a constant value as possible in order to maintain a uniform degree of brilliance of illumination therefrom and to maintain the quality of the light produced by the arc, any appreciable variation in the arc length not only altering the output of light from the arc but also changing the spectrum quality of the light.

10 In certain types of work, such as the lighting of motion picture sets, especially for color photography work, it is essential that the quantity of light be maintained at a uniform brilliance and any variation in the spectrum value of the light seriously affects the photographic results. It has been the common practice to employ high intensity arc lamps for this purpose to produce as brilliant illumination as possible but the character of control for the feeding of the carbons of such lamps has been such that uniform arc length 15 and uniform spectrum quality of the light has been substantially impossible to obtain.

15 It is also essential that the mechanism employed to feed the electrodes must be sufficiently sensitive in its response to variation in the arc length as to compensate for the burning away of electrodes in small increments to avoid sputtering or the creation of other noises which would interfere with the recording of sound upon the set.

20 It is an object of my invention therefore to provide a carbon arc lamp provided with automatic electrode feeding apparatus employed to be so sensitive as to maintain the light output and the spectrum quality of the light at constant values.

25 Another object of my invention is to provide a multiple-arc lamp which will effectively utilize the maximum amount of the current passing therethrough for the production of light and in which the set of electrodes for each arc is provided with its individual electrode feeding apparatus so connected as to respond accurately and sensitively to minute variations in the length of the arc between the associated electrodes.

30 Another object of my invention is to provide an arc lamp circuit for twin arcs in which the electrodes for each of the arcs is provided with its individual feeding mechanism, so connected in Wheatstone bridge circuits that the bridge circuit for one arc and the bridge circuit for the other 35 arc will contain a common leg.

Another object of my invention is to provide a control circuit for multiple-arc lamps in which a single ballast resistor is employed in circuit with all of the arcs and in which control devices for feeding each of the arcs are so connected in Wheatstone bridge circuits that the ballast resistor constitutes a common leg in bridge circuit for each of the control devices.

5 Other objects and advantages of my invention will be apparent from a study of the following 10 specifications, read in connection with the accompanying drawing, wherein

Fig. 1 is a diagrammatic view illustrating a twin arc lamp, the feeding mechanism for feeding the electrodes thereof, and the circuit arrangements 15 for including the ballast resistor in circuit with the arcs and the bridge circuits employed to supply current to the feeding devices; and

Fig. 2 is a schematic view of a modified wiring arrangement which may be used for a plurality of 20 arcs, either two or more.

Referring to the drawing, I have illustrated my arc lamp control circuit in Fig. 1 as applied to twin arcs A and B, the arc A of which may comprise a pair of electrodes A—1 and A—2 adapted to be secured in any suitable holders A—3 and A—4, respectively. The holders A—3 and A—4 are so connected to feeding apparatus as to permit the ready feeding of the electrodes A—1 and A—2 toward and away from each other, 30 such feeding apparatus being diagrammatically illustrated herein as including gear racks A—5 and A—6 attached respectively to the holders A—3 and A—4, the gear racks A—5 and A—6 meshing with a pinion A—7 which is adapted to 35 be driven by the armature A—8 of a small direct current electric motor AM, suitable reduction gearing being preferably interposed between the armature A—8 and the pinion A—7, as will be understood by those skilled in this art, but which, 40 in order to avoid unnecessarily complicating the drawing, has been omitted herein.

Similarly, the arc B may comprise a pair of electrodes B—1 and B—2, identical with the electrodes A—1 and A—2, adapted to be held in suitable holders B—3 and B—4 to which are attached gear racks B—5 and B—6 meshing with a pinion B—7 driven by the armature B—8 of a separate and individual motor BM.

The circuit for supplying current to the arcs 50 A and B may be termed the "arc" circuit and includes a ballast resistor R connected in series circuit relation with and disposed between the two arcs A and B so that the current supplied from a suitable source through conductors L—1 55

and L-2 will extend from line conductor L-1 through conductor 20, the electrodes A-2 and A-1, thence through the conductor 21, ballast resistor R, conductor 22, electrodes B-2 and B-1 and thence by way of conductor 23 to line conductor L-2.

The motor AM for feeding the electrodes A-1 and A-2 toward and away from each other may be connected in a Wheatstone bridge circuit, two legs of which are formed by the arc A and ballast resistor R, respectively, while the other two legs of which are formed by an auxiliary circuit including resistor AR having a movable tap 24 adapted to connect with any point along the resistor AR. The resistor AR is illustrated as being connected between line conductor L-1 and the far end 25 of the ballast resistor R as by means of conductors 26 and 27, respectively, so that that portion of the resistor AR which lies to the left of the tap 24 will constitute one leg of the bridge circuit while that portion of the resistor AR which lies to the right of the tap 24 will constitute the other leg of the circuit. The armature A-8 of the control motor AM for the arc A is preferably connected directly across the mid terminals of the Wheatstone bridge circuit so formed; that is, the armature A-8 is connected directly between the near terminal 28 of the ballast resistor R and the tap 24 by means of conductors 29 and 30.

By reference to that portion of the circuit hereinbefore described, it will be apparent that the motor armature A-8 will receive current due to any unbalancing of the bridge circuit, the direction of flow of current (and thus the direction of rotation of the armature A-8) depending upon whether the arc length has increased or decreased beyond a value necessary to balance the circuit.

Similarly, the ballast resistor R and the arc B constitute two legs of a second Wheatstone bridge circuit, the other two legs of which are formed by a second auxiliary resistor BR having a movable tap 31 corresponding to the tap 24, the resistor BR being connected between the near terminal 28 of the ballast resistor R and line conductor L-2 by means of conductors 32 and 33, respectively, the portion of the resistor BR lying to the right of the tap 31 constituting one leg of the bridge circuit while that portion which lies to the left of the tap 31 constitutes the other leg.

The motor armature B-8 is similarly connected between the mid points of this circuit, that is, between the far terminal 25 of the ballast resistor R and the tap 31, by means of a pair of conductors 34 and 35, respectively. Thus any unbalancing of this second Wheatstone bridge circuit (ballast resistor R, arc B and resistor BR) as by lengthening or shortening of the arc B, will cause current to flow in one direction or the other through the armature B-8, causing the electrodes B-1 or B-2 to be moved toward or away from each other.

The motors AM and BM should be selected with as low inertia value as possible so that the armatures thereof may readily respond to relatively small currents passing therethrough. The field windings of the motor may be selected of any suitable strength to insure sensitive response to small currents passing through the armatures and should be constantly energized as by connecting the field windings A-9 and B-9 of the motors in permanent series relation across the source of supply line conductors L-1, L-2, as by means of conductors 36 and 37, a suitable resistor 38 being interposed in the circuit if desired to limit or regulate the current supplied to the field windings.

As will be understood by those skilled in this art, it is the common practice in arc lamp circuits to determine the desired voltage and current to be supplied to the arc for efficient operation thereof and then to select a ballast resistor capable of absorbing and dissipating the remaining line voltage. By employing twin arcs connected as set forth herein, each of the arcs acts as a resistance for the other arc, reducing the amount of ballast resistance which would be required to be used with either of the arcs singly, thus permitting substantially twice the amount of illumination to be produced by the same amount of current which would otherwise be required for the operation of a single arc employing the same carbons and the same current density.

By employing the circuit for the arcs and the circuit for the armatures of the control motors as set forth herein, extremely sensitive and accurate control of the arc lengths of each of the arcs may be accomplished to maintain each of the arcs at a uniform length and thus maintain uniformity of quantity of light and quality of light produced thereby. For example, my system may be employed to be operated from a power supply line furnishing 115 volts by selecting the ballast resistor R to have a voltage drop of about 41 volts when employed with electrodes and arc lengths in the arcs A and B such that a voltage drop of 37 volts is impressed across each of the arcs. With this arrangement, the auxiliary resistor AR may be so selected as to carry approximately four to six amperes of current, the tap 24 being moved along the resistor R until the resistance ratio of the portions of the auxiliary resistor AR on opposite sides of the tap 24 is just equal to the "optimum" or desired resistance ratio of the arc A to the resistance of the ballast resistor R when the arc A is at its most desirable length, the auxiliary resistor AR thus supplying a reference resistance ratio just equal to the optimum desired resistance ratio between the arc A and the ballast resistor circuit. Thus when the arc A is at its proper, most desirable length, the potential across the arc will just equal the reference resistor potential and no current will flow through the circuit for the armature A-8.

Similarly, the resistor BR is selected to pass four to six amperes when the legs 41 and 42 thereof are so balanced in the circuit as to permit no current to flow through the armature B-8.

Any lengthening of the arc A will increase the voltage drop in the leg A of the bridge circuit described by the arc A with a corresponding drop in the current flowing through arc A and resistor R, thereby causing a lowering of the voltage drop across the terminals of the resistor R. As the voltage between conductor L-1 and the tap 24 will remain substantially constant, an unbalanced condition will occur in the bridge circuit, causing current to flow through the motor armature A-8 in the direction necessary to move the electrodes A-1 and A-2 toward each other. By maintaining the current flow through the resistor AR at a relatively high value in proportion to the current required to flow through the armature A-8 to achieve movement thereof, the current flowing through the armature will not appreciably change the IR drop in the leg 39 of the bridge circuit and accurate balancing of the legs 39 and 40 of the bridge circuit is permitted, insuring that the only unbalancing of the circuit will occur by reason of variation in the length of the arc A.

Similarly, in the bridge circuit described by the

arc B, resistor R and legs 41 and 42 of the auxiliary resistor BR, any variation in the length of the arc B will similarly cause the armature B—8 to respond sensitively thereto. I have found by 5 actual experiments that a change in voltage drop across the arcs A or B of from 1 to $1\frac{1}{2}$ volts is sufficient to cause the armatures A—8 or B—8, respectively, to respond to such change and to feed the electrodes in the proper amount to 10 maintain the voltage drop across each of the arcs, respectively, within limits of from 1 to $1\frac{1}{2}$ volts at all times during operation of the lamp, and I am thus enabled to maintain the spectrum quality of the lights produced by each of the 15 arcs at a constant value and to maintain the quantity of light produced by the arcs within a limit of $\pm 2\frac{1}{2}\%$.

It will be observed that while I utilize twin arcs connected in series relation with each other, I 20 provide two distinct Wheatstone bridge circuits, one for each of the arcs, though I employ the ballast resistor R as a common leg in each of the bridge circuits and I am thus enabled to employ the accuracy and sensitivity of a Wheatstone 25 bridge control circuit with twin arcs.

In Fig. 2 I have illustrated a modified set of circuits which adapts my system for use with either two or more than two arcs, three being illustrated in Fig. 2 as connected in an arc circuit 30 across the supply line L—1 and L—2 with a common ballast resistor R in series therewith. An auxiliary circuit is illustrated as including the control resistors associated with each of the arcs A, B and C, such circuit either including one long 35 auxiliary resistor or a series of short resistors, one associated with each of the arcs, to provide a series of reference potentials along the auxiliary circuit, one equal to the optimum potential between the successive arcs so as to provide points 40 of connection associated with each of the arcs across which the armatures of the motors or other electromotive feeding means may be connected in such manner as to be supplied with current in correspondence with changes in the potential 45 across the associated arc. For example, a section of the long resistor or a short resistor designated by the reference character AR corresponds to the resistor AR illustrated in Fig. 1 while another section of the long resistor or a short resistor to be 50 associated with the arc B is designated by the reference character BR.

A similar section of the long resistor or a short individual resistor is associated with the arc C, by employing the auxiliary resistors AR, BR and 55 CR connected as illustrated in Fig. 2, the motor armatures A—8, B—8 and C—8 associated with the respective arcs A, B and C may be connected as indicated in Fig. 2, the motor armature A—8 associated with the arc A having one of its terminals connected to the conductor 50 which extends 60 between arc A and arc B, while the other of its terminals is connected to an adjustable tap 51 engaging the resistor AR. Similarly the motor armature B—8 associated with the arc B may be 65 connected to conductor 52 extending between arcs B and C, while the other of its terminals connects with a tap 53 engaging resistor BR, while the motor armature C—8 has one of its terminals connected to conductor 54 and the other of its 70 terminals connected to a tap 55 engaging the resistor CR.

In effect, such connection provides a plurality of "bridge" circuits, the bridge circuit associated with the arc A including as one of its legs the arc 75 A, as another of its legs the remainder of the arc

circuit including arcs B and C and ballast resistor R, while the control resistor AR constitutes a third leg of this bridge circuit and the combined resistors BR and CR constitute the fourth leg.

As was described with reference to Fig. 1, the amount of current flow through the resistors AR, BR and CR should be selected of a relatively high value in proportion to the amount of current required to flow through the motor armature A—8, B—8 or C—8 to cause these armatures to turn. 5 Thus by properly selecting the resistance for the resistor AR such that when the arc A is at its proper length, no current will flow through the motor armature A—8, and it follows that any lengthening of the arc A will increase the voltage 10 drop in the leg A of its bridge circuit with a corresponding drop in the current flowing through arc A and the remainder of the main circuit for arc A (namely, arcs B and C and resistor R), thereby causing a lowering of the voltage drop 15 between conductor 50 and line conductor L—2. Since the voltage between line L—1 and the tap 20 51 will remain substantially constant, an unbalanced condition will occur causing current to flow through the motor armature A—8 in the direction 25 necesasry to move the electrodes of arc A toward each other.

Similarly, any change in the voltage drop 30 across arc B, as by lengthening of arc B, would cause an unbalance of the bridge circuit for arc B (this circuit including as one leg arcs A and B, as another leg arc C and ballast resistor R, as a third and fourth leg the sections of the auxiliary resistor AR lying to the right and to the left of the tap 53), and hence current will flow through 35 the motor armature B—8 in a direction necessary to move the electrodes of arc B toward each other.

Similarly, any change in arc length of arc C will unbalance its bridge circuit (which includes 40 as one leg arcs A, B and C, as another leg ballast resistor R, as the third and fourth legs the sections of the auxiliary resistor AR, BR and CR lying to the right and left of the tap 55).

As will be understood by those skilled in this art, the field windings for the control motors for 45 each of the arcs may be connected in series relation across the supply line as indicated at A—9, B—9 and C—9 in Fig. 2.

With the form of the device illustrated in Fig. 2, it will be apparent that the effect of a sensitive 50 Wheatstone bridge circuit for each of the control motors may be accomplished even though the several arcs to be controlled are connected in series relation with each other and with a common ballast resistor, each of the control motors functioning with its associated arc to automatically 55 and sensitively respond to changes in the length of the associated arc to correct for such changes and thus to maintain each of the arcs at a constant length throughout the life of the electrodes. 60 While I have illustrated only three arcs in Fig. 2, it will be apparent to those skilled in the art that with proper voltages impressed upon the supply line any desired number of arcs may be connected in series circuit relation, any variation in 65 the length of one of the arcs being corrected so instantaneously as to prevent such fluctuation in one of the arcs from affecting the brilliance or spectrum value of the light produced by the other arcs.

While I have shown and described the preferred embodiment of my invention, I do not desire to be limited to any of the details of construction shown or described herein, except as defined in the appended claims.

I claim:

1. In an arc lamp circuit, two sets of electrodes comprising two arcs, a ballast resistor interposed in series relation with said arcs and disposed in circuit between them, individual electromotive feeding means for each of said sets of electrodes for moving the associated set of electrodes toward and away from each other, a control circuit for each of said feeding means comprising a Wheatstone bridge circuit, the legs of one branch of which are formed respectively by the associated arc and the ballast resistor, and the legs of the other branch of which are formed by auxiliary resistors, and means cross connecting the electromotive means between the said branches.
2. In a system for controlling the feeding of the electrodes of twin arcs to maintain the length of each of said arcs at a substantially constant value, an electromotive feeding means for each of said arcs, an arc circuit including a ballast resistor in series with and disposed between said arcs, and means connecting the electromotive means associated with each arc in a Wheatstone bridge circuit including the associated arc as one of the legs thereof, said ballast resistor being common to both of said bridge circuits.
3. In an arc lamp circuit, two sets of electrodes comprising two arcs, a ballast resistor interposed in series relation with said arcs and disposed between them, individual electromotive feeding means for each of said sets of electrodes for moving the associated set of electrodes toward and away from each other, a control circuit for each of said feeding means comprising a Wheatstone bridge circuit, the legs of one branch of which are formed respectively by the associated arc and the ballast resistor, and the legs of the other branch of which are formed by auxiliary resistors, and means cross connecting the electromotive means between the said branches, said auxiliary resistor for each circuit being of relatively low resistance as compared with the resistance of said feeding means whereby the current in said auxiliary resistor will be relatively great as compared with the current required for response by said electromotive means.
4. In an arc lamp circuit, two sets of electrodes comprising two arcs, a ballast resistor interposed in series relation with said arcs and disposed in circuit between them, individual feeding means for each of said sets of electrodes including an electric motor, a control circuit for each of said feeding means comprising a Wheatstone bridge circuit, the legs of one branch of which are formed respectively by the associated arc and the ballast resistor, and the legs of the other branch of which are formed by auxiliary resistors, and means cross connecting the armature of the motor between said branches.
5. In an arc lamp circuit, a plurality of sets of electrodes each forming an arc, ballast resistor means interposed in series relation with said arcs and disposed between said arcs, individual feeding means for each of said sets of electrodes including an electric motor, a control circuit for each of said feeding means, each of said circuits comprising a Wheatstone bridge, the legs of one branch of which are formed respectively by the associated arc and the ballast resistor, the legs of the other branch of which are formed by auxiliary resistors, and means cross-connecting the armature of the motor between said branches, the ballast resistor disposed between each pair of adjacent arcs constituting a common leg in the

bridge circuits associated with the respective arcs.

6. In an arc lamp circuit, two sets of electrodes comprising two arcs, a ballast resistor interposed in series relation with said arcs and disposed between them, individual feeding means for each of said sets of electrodes including an electric motor, means connecting the field windings of said motors for constant predetermined excitation, a control circuit for each of said feeding means, each of said circuits comprising a Wheatstone bridge, the legs of one branch of which are formed respectively by the associated arc and the ballast resistor, and the legs of the other branch of which are formed by auxiliary resistors, and means cross-connecting the armature of the associated motor between said branches, the ballast resistor constituting a leg common to both of said bridge circuits.

7. In a system for so controlling the feeding of electrodes of a plurality of series connected arcs as to maintain the length of each of said arcs at a substantially constant value, the combination of: an arc circuit extending across a supply line and including a plurality of elements connected in series comprising a plurality of sets of electrodes for a plurality of arcs and a ballast resistor means; an auxiliary circuit connected across the supply line and including selected resistance portions associated respectively with each of said arcs; individual electromotive feeding means for each set of electrodes; circuit means connecting each of said feeding means to one of the electrodes of the associated arc at a point in said arc circuit between the associated arc and one of the remaining elements in the arc circuit; and circuit means connecting said feeding means to said auxiliary circuit at a point between the associated resistance portion and one other resistance portion.

8. In a system for so controlling the feeding of electrodes of a plurality of series connected arcs as to maintain the length of each of said arcs at a substantially constant value, the combination of: an arc circuit extending across a supply line and including a plurality of elements connected in series comprising a plurality of sets of electrodes for a plurality of arcs and a ballast resistor means; an auxiliary circuit connected across the supply line and including selected resistance portions associated respectively with each of said arcs; individual electric motors for feeding each set of electrodes; circuit means connecting the armatures of each of said motors to one of the electrodes of the associated arc at a point in said arc circuit between the associated arc and one of the remaining elements in the arc circuit; circuit means connecting said armatures to said auxiliary circuit at a point between the associated resistance portion and one other resistance portion; and means connecting the fields of each of said motors in circuit across said supply line.

9. In a system for so controlling the feeding of electrodes of a plurality of series connected arcs as to maintain the length of each of said arcs at a substantially constant value, the combination of: an arc circuit extending across a supply line and including a plurality of elements connected in series comprising a plurality of sets of electrodes for a plurality of arcs and a ballast resistor means; an auxiliary circuit connected across the supply line and including selected resistance portions associated respectively with each of said arcs; individual electromotive feed-

ing means for each set of electrodes; circuit means connecting each of said feeding means to one of the electrodes of the associated arc at a point in said arc circuit between the associated arc and one of the remaining elements in the arc circuit; circuit means connecting said feeding means to said auxiliary circuit at a point between the associated resistance portion and one other resistance portion, the resistance in said auxiliary circuit being low relative to the resistance of said feeding means.

10. In a system for so controlling the feeding of electrodes of a plurality of series connected arcs as to maintain the length of each of said arcs at a substantially constant value, the combination of: an arc circuit including a ballast resistor and a plurality of sets of electrodes connected in series relation with each other to comprise a plurality of arcs; individual electromotive feeding means for each of said sets of electrodes for moving the associated set of electrodes toward and away from each other; an auxiliary resistor associated with each of the arcs and connected in parallel with its associated arc and said ballast resistor; and means connecting one terminal of each of said feeding means between

its associated arc and the ballast resistor and connecting the other terminal of said feeding means to the auxiliary resistor associated with that arc to supply said feeding means with current in correspondence with variations in the resistance of the associated arc. 5

11. In a system for so controlling the feeding of electrodes of a plurality of series connected arcs as to maintain the length of said arcs at a substantially constant value, the combination of: 10 an arc circuit extending across a supply line including a plurality of sets of electrodes connected in series to comprise a plurality of arcs; an auxiliary circuit connected across the supply line and including selected adjustable resistance portions associated respectively with each of said arcs; individual electromotive feeding means for each set of electrodes; circuit means connecting the feeding means for each arc to the arc circuit between the associated arc and the next adjacent arc and to the auxiliary circuit between the resistance portion for the associated arc and the resistance portions for the remaining arcs; and means for manually adjusting the resistance of said resistance portions. 15 20 25
